CLAIM

The ornamental design for a control device, as shown and described.

DESCRIPTION

FIG. 1 is a perspective view of a control device embodying the claimed design.

FIG. 2 is a right side view thereof.

FIG. 3 is a left side view thereof.

FIG. 4 is a rear view thereof.

FIG. 5 is a front view thereof.

FIG. 6 is a top view thereof; and,

FIG. 7 is a bottom view thereof with a portion of the environment removed to improve visibility of the control device.

The claimed design is shown in solid lines in the drawings. The portions of the drawings shown in broken lines form no part of the claimed design. The portions of the drawings shown in broken lines having unequal segments illustrate the boundary of the claimed design and form no part of the claimed design.

The present disclosure relates to a control device, such as a control grip for a work vehicle.
